Primary Examiner — Paula Allen Greene*(74) Attorney, Agent, or Firm* — Law Office of Jeff Williams PLLC; J. Oliver Williams(57) **CLAIM**

The ornamental design for a headphone, as shown and described.

DESCRIPTION

FIG. 1 is an oblique view of a headphone showing the new design;

FIG. 2 is a front view of the headphone of FIG. 1.

FIG. 3 is a rear view of the headphone of FIG. 1.

FIG. 4 is a top view of the headphone of FIG. 1.

FIG. 5 is a bottom view of the headphone of FIG. 1.

FIG. 6 is a right view of the headphone of FIG. 1; and, FIG. 7 is a left view of the headphone of FIG. 1.

The broken lines depict portions of the headphone that forms no part of the claimed design.

1 Claim, 7 Drawing Sheets(56)
